(57) **CLAIM**

We claim the ornamental design for a footwear care machine, as shown and described.

DESCRIPTION

FIG. 1 is a perspective view of a footwear care machine showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a front perspective view of a footwear care machine showing a state in which doors are open;

FIG. 9 is a left perspective view thereof;

FIG. 10 is a front view thereof;

FIG. 11 is a rear view thereof;

FIG. 12 is a left-side elevation view thereof;

FIG. 13 is a right-side elevation view thereof;

FIG. 14 is a top plan view thereof; and,

FIG. 15 is a bottom plan view thereof.

The broken lines represent portions of the Footwear care machine that form no part of the claimed design.
